BY
Mr. A. Campfield.
ATTORNEY.

UNITED STATES PATENT OFFICE.

HONESTUS M. ALBEE, OF NUTLEY, NEW JERSEY.

WOODWORKING-MACHINE.

No. 926,452.

Specification of Letters Patent.

Patented June 29, 1909.

Application filed May 16, 1908. Serial No. 433,158.

To all whom it may concern:

Be it known that I, HONESTUS M. ALBEE, a citizen of the United States, residing at Nutley, in the county of Essex and State of New Jersey, have invented certain new and useful Improvements in Woodworking-Machines; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to a machine for cutting out patterns from wood, and is adapted to give a fine edge to the cut made in the wood and permit of the cut extending up into small corners so as to make a complete design, and is designed to particularly take the place of hand cutting which is now necessary in wooden plaques and similar ornamental devices made of wood and supplied with a design. These plaques, as now furnished, are printed with a configuration which is treated sometimes by pyrography, but in other forms the design is cut out of the first layer of veneer, of which the plaque is made up, and after this cut design is treated it is known in the trade as Flemish art. These designs, as heretofore said, have been cut out by hand, which makes them expensive and also gives a finish that is not clean on the edges of the cut, and the effect is also marred by a cut running beyond the point where it should stop. This machine does this cutting by a quick reciprocation of a chisel-shaped knife, and the design can be moved along under the knife, similar to wood that is submitted to a hand saw or goods on a sewing machine. The machine also embodies an adjustable table which can be operated manually and on which the desired penetration of the wood can be adjusted, this penetration being kept uniform by the pressure supplied to the table which forces the wood against the knife or chisel.

The invention is illustrated in the accompanying drawings, in which Figure 1 is a face view of the machine, and Fig. 2 is a section of the table. Fig. 3 is a plaque showing part of it cut out, and Fig. 4 is a detail view of a veneered plaque or piece of wood, and illustrating diagrammatically the operation of the knife of the machine on the wood.

The machine consists of a suitable base 10

forming a support for a table 11 on which is mounted a machine-frame 12 which can be of any well known construction, and I find that the mechanism in a sewing machine is well adapted for the purpose, this machine being driven as usual by a belt 13, and the operation of the machine acting to rapidly reciprocate a chisel-shaped knife 14. Underneath the machine is a treadle 15 which, when operated by the foot, acts to pull down a rod 16 which is fastened at its upper end to the end of the narrow portion 17 of a plunger 18 which is adapted to slide in a cylinder 19. A spring 20 abuts on one end of the shoulder formed by the piston 18 and its narrow portion, and abuts on its other end on a cap 21. A cap 23, on the other end of the cylinder 19, receives the shoulder 23^a of the piston 18, and acts as a stop for the upward movement of the piston.

The cylinder can be adjusted by rotating the nut 22 which turns on the screw-threaded exterior of the cylinder 19 and is locked in place by a lock-nut 24. I prefer to provide the lock-nut 24 with a lever 25 which projects, as in Fig. 1, from a slot 26 in the table 11 and provides for the easy unlocking of the lock-nut 24, and then by a rotation of the nut 22, the cylinder 19 can be moved toward and from the knife 14. A tablet 27 is mounted on the end of the plunger 18 and serves to hold the work to be operated on.

In Fig. 3 I show one design of plaque 28. These plaques are provided with lines 29, which lines are afterward used in ornamenting the plaque, or any other piece of wood-work, by pyrography, or in this process by cutting away the design on the lines 29 and uncovering the portions 30 of one of the lower veneers, these veneers 31 being assembled, as shown in Fig. 4, to make up the plaque. When it is desired to use the machine, the foot lever 15 is operated, after the height of the table has been adjusted by means of the nut 22, and the machine being in operation, the plaque is placed with one of its lines to be cut out underneath the knife 14 which is rapidly reciprocating, and the treadle 15 being gradually released, the plaque is placed underneath the knife at the exact point where the cut is to be made, and then by a slight pressure with the hand the work can be fed so that the knife 14 will gradually pass along transversely of the line 110 to be operated on, cutting into the material for a partial penetration. When the out-

line of one recessed portion has been traversed, the material of the upper layer of veneer to be removed can be gouged or chiseled from its place, the adhesive between 5 the veneers giving way to the pressure, or if the block is made of one piece, the wood itself is taken out by a chisel or router from between the cuts.

The operation of this machine is rapid and 10 gives a better product than the hand cutting, and eliminates the danger of bodily injury to the operators, since there are no knives to slip from the grasp nor from the wood. When the plaque has been cut out, it is 15 usually treated by the pyrographic process and the recessed portions are burned, thus saving considerable time over a process where the burning is done to the required depth.

20 It will of course be understood that the knife 14 will reciprocate without turning in its bearings so that the cutting or chiseled edge is always cutting in the same plane. This stability can be accomplished by the 25 well known use of a slot and feather or by making the shank of the knife square in a square bearing.

Having thus described my invention, what I claim is:—

30 1. A machine of the kind described comprising a support, a machine-frame mounted on the support, a knife in the machine-frame, the knife having a cutting edge on its end, mechanism within the machine-frame for rapidly reciprocating the knife, a cylinder mounted on the machine-frame, a piston in the cylinder and engaging one end thereof, a reduced portion projecting from the lower end of the cylinder, a spring having one end

abutting on the piston and having its other 40 end abutting on the end of the cylinder, the cylinder having a screw-threaded exterior, a nut on the screw-threaded exterior and engaging the under side of the machine-frame, a tablet mounted on the top of the 45 piston and underneath the knife, and a treadle connected to the lower end of the piston to operate it.

2. A machine of the kind described comprising a support, a machine-frame mounted 50 on the support, a knife in the machine-frame, the knife having a cutting edge on its end, mechanism within the machine-frame for rapidly reciprocating the knife, a cylinder mounted on the machine-frame, a piston in 55 the cylinder and engaging one end thereof, a reduced portion projecting from the lower end of the cylinder, a spring having one end abutting on the piston and having its other end abutting on the end of the cylinder, the 60 cylinder having a screw-threaded exterior, a nut on the screw-threaded exterior and engaging the under side of the machine-frame, a lock-nut on the screw-threaded exterior of the cylinder and bearing against 65 the first nut, a lever projecting from the lock-nut for its manipulation, a tablet mounted on the top of the piston and adapted to form a work holder, and a treadle secured to the lower end of the piston for its manual 70 manipulation.

In testimony, that I claim the foregoing, I have hereunto set my hand this 13th day of May 1908.

HONESTUS M. ALBEE.
